UNITED STATES PATENT OFFICE.

EMIL STEFFENS, JR., AND HOMER A. JONES, OF RUTHERFORD, NEW JERSEY.

DESIGN FOR A LABEL-BLANK.

43,168.

Specification for Design.

Patented Oct. 15, 1912.

Application filed July 20, 1912. Serial No. 710,709. Term of patent 3½ years.

To all whom it may concern:

Be it known that we, EMIL STEFFENS, Jr., and HOMER A. JONES, citizens of the United States, residing at Rutherford, Bergen county, New Jersey, have invented a new, original, and ornamental Design for a Label-Blank, of which the following is a specification, reference being had to the accompanying drawing, forming part hereof.

The figure is a face view of a label blank showing our new design.

We claim:

The ornamental design for a label blank, as shown.

EMIL STEFFENS, JR.
HOMER A. JONES.

Witnesses:

MARIE F. WAINRIGHT,
CHAS. A. BRODET.
